ELECTROMAGNETIC RELAY

Clark V. Bullen, Rockford, Ill., and John T. R. Wilson, Sacramento, Calif., assignors to Barber-Colman Company, Rockford, Ill., a corporation of Illinois

Application September 10, 1956, Serial No. 609,006

5 Claims. (Cl. 200—93)

This invention relates to an electromagnetic relay of 15 the polarized type having an armature movable into different active positions in response either to direct currents of opposite polarities or alternating currents of opposite phases.

The general object of the invention is to provide a polarized relay which, as compared to prior relays of the above character, is more sensitive to small signal currents, is more positive and reliable in its operation, and is of simpler construction.

Another object is to insure reliable operation of a polarized relay of the above character by moving the armature to a positively defined neutral position when the different signal currents are of negligibly small value.

A more detailed object is to provide a novel arrangement of flux producing coils and magnetic circuits for attraction of a freely floating armature selectively to any of three positively defined and angularly spaced positions under different current conditions in the coils.

The invention also resides in the novel and simple construction of the relay core providing the magnetic circuits.

Other objects and advantages of the invention will become apparent from the following detailed description taken in connection with the accompanying drawings, in which:

Figure 1 is a perspective view of a relay embodying the 40 novel features of the present invention with the protective cover removed.

Fig. 2 is a plan view with the cover removed, some parts being broken away and shown in section.

Fig. 3 is a sectional view taken along the line 3—3 of 45 Fig. 2.

Fig. 4 is a fragmentary exploded perspective view of one pole piece and its encircling coil.

Fig. 5 is a sectional view taken along the line 5—5 of Fig. 2 with the cover in place.

Figs. 6, 7 and 8 are enlarged schematic plan views showing the positions of the armature under different current conditions.

The invention is shown in the drawings for purposes of illustration embodied in an electromagnetic relay having an armature 10 which is attracted into each of three different positions with respect to a core 11 selectively in response to different current conditions in a signal coil means 12 associated with the core. When the signal current is of zero or a negligibly small value, the armature is attracted to a neutral or null position (Figs. 2 and 6) by magnetic flux of an energizing or polarizing flux means 13. Signal currents of larger value and different characteristics or senses, for example, direct currents of opposite polarity or alternating currents of opposite phase, each produce a flux cooperating with the energizing flux to provide a resultant flux attracting the armature to the corresponding one of its other two positions shown in Figs. 7 and 8. In its different positions, the armature cooperates with contacts 14, 15 and 16 to control different electrical circuits (not shown) extending through the contacts.

To achieve sensitivity to small signal currents and insure

2

reliable operation of the relay, the present invention contemplates free movement of the armature 10 into each of its three positions which are defined positively by seats angularly spaced from each other about a cavity or recess 17 receiving the armature. For this purpose, the core comprises three pole pieces 18, 19 and 20 converging toward but terminating short of each other in end faces spaced apart to form the cavity. The three armature seats are defined by abutments 21, 22 and 23 (Figs. 6, 7 and 8) 5 rigid with the pole pieces and facing inwardly toward the cavity and each seat is disposed between two different pole pieces for attraction of the armature into the seat by magnetic flux threading the gap between the pieces. The abutments may be formed on or separately from the pole pieces, the two abutments 22 and 23 defining the seat for the neutral position of the armature in this instance being the end faces of two of the pole pieces 19 and 20. The third abutment 21 is the exposed face of a sheet 24 of the electric current conductive metal of U-shaped cross section telescoping with and secured to the end portion of the third or common pole piece 18.

Flux paths across the gaps between the adjacent ends of the pole pieces are completed by magnetic connections 25 joining the pieces at points spaced from their end faces. To simplify the construction of the core, the pole pieces are straight magnetic bars which are formed separately from the connections but are secured in abutting relation therewith to form closed magnetic joints. While two connections may be used, there are three in this instance of 20 arcuate shape arranged in a circle on one end of a cylindrical base 26 of nonmagnetic material and having their adjacent ends spaced apart to receive and abut the outer end portions of the pole pieces which are disposed radially of the base.

The pole pieces 18, 19 and 20 and the connections 25 are laminated and are of rectangular cross section with the same thickness axially of the base 26, the connections being secured to the latter by screws 27 extending through holes in the laminations and the base and threaded into a bottom housing plate 28 of insulating material. To secure the pole pieces in place, flat plates 29 overlapping the abutting end portions of the connections and the pieces are clamped against the same by screws 30 threaded into the housing plate and extending through holes in the base and longitudinal slots 31 (Fig. 2) which are formed in the pieces for adjustment of the latter radially relative to the base. At their inner ends, the pole pieces are flat, the two pieces 19 and 20 defining the neutral seat being tapered outwardly for increased flux densities at the ends.

While the means 13 providing the energizing flux in the 50 tapered pole pieces 19 and 20 for attracting the armature 10 into its neutral seat may constitute permanent magnets in the case of unidirectional signal current, it is preferred to use one or more multiple turn windings or coils which may be utilized for alternating as well as direct 55 current signals and whose energization may be varied to change the amount of energizing flux after assembly of the relay parts. In this instance, there are two energizing coils 13 one for each of the tapered pole pieces and each wound around a bobbin 32 of insulating material 60 which telescopes closely over and is supported on the associated pole piece while leaving the inner end portion of the latter exposed. The signal coil means 12 also comprises one or more coils, herein one, wound on an insulating bobbin 33 telescoping over the third pole piece 18 and the laterally spaced parallel legs of the U-shaped sheet 24. Due to formation of the pole pieces 18, 19 and 20 as 65 elongated members separate from the connections 25, the bobbins may be telescoped over the pieces after the coils are wound and before assembly of the pieces to the connections.

To complete the electrical circuits through the contacts

14, 15 and 16, the armature itself is adapted to conduct current and, thereby, constitute a movable contact of the relay. While the armature may be a ball, it is preferred to use a cylinder as shown for engagement with the fixed contacts along lines rather than at points. Herein, the armature comprises a stack of axially aligned annular laminations 34 (Fig. 5) of magnetic material secured rigidly together as by cement and telescoping over a pin 35 which projects from opposite ends of the stack. To improve its conductivity, the armature preferably is plated on its exterior with a highly conductive material such as silver.

The conductive sheet 24 on the common pole piece 18 provides a common contact 14 engageable with the armature in both of its active positions. The other contacts 15 and 16 are formed as reversely bent ends of fingers 36 projecting inwardly from flat resilient strips 37 of conducting material. Herein, the sheet and the strips are formed of hammered silver approximately .002 of an inch thick. The strips are secured in slots formed in lugs 38 on the inner ends of the energizing coil bobbins 32 with each of the contacts thereon projecting between the common pole piece and the associated one of the tapered pole pieces 19 and 20, the contacts thus being resiliently supported for sliding contact with the armature. Thin sheets 39 of insulation separate the contacts from the associated pole pieces and the ends of the tapered pole pieces 19 and 20 may, if desired, also be covered by thin sheets 40 of insulation as shown in Fig. 8.

To confine the armature 10 axially within the cavity 17, the bottom housing plate 28 and an inverted cup-shaped cover 41 of insulating material carry lugs 42 projecting toward the cavity and providing flat abutment faces engageable with the projecting ends of the armature pin 35 but spaced apart to provide clearance for free sliding of the armature without cocking, the ends of the pin being rounded to facilitate such sliding. Electrical circuits to be completed through the contacts are connected to the respective contact strips 37 and the sheet 24 which project upwardly through the top of the cover 41 (Fig. 5).

The operation of the relay may best be described in connection with Figs. 6, 7 and 8 which show the distribution of flux under different conditions of current flow through the coils 12 and 13. Assuming no current is flowing in the signal coil 12 and that direct current is flowing in equal amounts in the energizing coils to produce a flux whose direction in the tapered pole piece 19 on the left is toward the cavity 17 and in the tapered pole piece 20 on the right is away from the cavity, the flux will be distributed generally as shown by the lines 43 in Fig. 6, the arrowheads indicating direction. Substantially all of this flux traverses the gap between the tapered pole pieces to attract the armature against the two abutments 22 and 23 thereof and into the neutral seat defined thereby. As it leaves the right pole piece, this flux divides between a path through the core connection 25 abutting both pole pieces and another path extending past the outer end of the common pole piece 18 and through the other two connections as indicated by the lines 43, the major portion of this flux following the shorter path. In its neutral position, the armature is spaced from and out of engagement with all of the fixed contacts 14, 15 and 16. Flux in the common pole piece 18 is substantially zero because the flux from one energizing coil tending to thread this pole piece opposes that of the other energizing coil.

With the same energizing flux and with signal current flowing in the coil 12 in a direction to produce a flux therein whose direction is away from the cavity 17, such flux tends to follow two paths represented by arrowed lines 44 in Fig. 7 and extending through the respective tapered pole pieces 19 and 20. The direction of this flux with respect to the energizing flux is the same in the left pole piece 19 but is opposite in the right pole piece 20. Under these conditions, the resultant flux in the air gap between the left pole piece and the common pole piece

18 is greater than the flux in either of the other gaps, the flux in the right pole piece and therefore in the other gaps being substantially zero when the amount of signal current flux in each tapered pole piece is equal approximately to the energizing flux. Thus, the armature is attracted into its active seat defined by the common abutment 21 and the abutment face 22 of the left pole piece and engages the left contact 15 and the common contact 14 to complete the external circuit between the contacts.

Upon energization of the signal coil 12 with current flowing therethrough in the opposite direction, the signal flux follows the same paths as before but in opposite directions as indicated by arrowed lines 45 in Fig. 8. The resultant flux in the gap between the right tapered pole piece 20 and the common pole piece 18 then is greater than in either of the other gaps and the armature is attracted into the corresponding seat to engage the right contact 16 and complete the circuit between the latter and the common contact 14. Upon deenergization of the signal coil, the armature again is attracted into the neutral seat by the energizing flux. In the case of alternating currents in the energizing and signal coils 12 and 13, the operation is substantially the same when the signal current is in phase or 180° out of phase with the energizing current; the arrowheads on the various flux path lines representing the instantaneous directions of the flux.

It will be apparent that the relay is reliable in its operation because the armature 10, by virtue of its positive seating against the abutments 21, 22 and 23 in each of its three positions, tends to remain in such position when subjected to vibrations. Such positive seating is made possible by a free floating mounting of the armature and by the angular spacing of the pole pieces 18, 19 and 20 with the signal and energizing coils 12 and 13 arranged to direct magnetic flux selectively across only one of the three gaps between adjacent pole pieces at a time. The formation of the pole pieces as straight bars separate from the connections 25 facilitates mounting of the coils thereon and enables the connections to be identical thereby simplifying manufacture and assembly of these parts.

We claim as our invention:

1. A relay having in combination, a hollow cylindrical base of nonmagnetic material, a magnetic core comprising three arcuate segments of the same construction extending around and secured against one end of said base in angularly spaced relation with their adjacent ends spaced apart and facing toward each other, three elongated magnetic pole pieces each disposed between and abutting said opposed ends of a different pair of said segments and projecting radially and inwardly therefrom toward but short of the other pole pieces to define a cavity, a magnetic armature smaller than and freely movable within said cavity, abutments rigid with said pole pieces and engageable with said armature to confine the movements thereof to three angularly spaced positions, a plurality of coils encircling said pole pieces and operable under different conditions of energization to produce a resultant flux attracting said armature selectively into each of said three different positions, and contact means cooperating with said armature to complete different electrical circuits when the armature is in said different positions.

2. A relay having, in combination, a core comprising first, second, and third elongated pole pieces of magnetic material connected together at their outer ends by magnetic members and converging toward each other with their inner ends spaced apart and defining a cavity, a magnetic armature smaller than and freely movable within said cavity and adapted to conduct electric current, a contact strip covering the inner end of said first piece, said strip and the inner ends of said second and third pieces abutting said armature and defining three angularly spaced seats therefor, two contacts one supported behind each of said seats between said first piece and the other pieces

for abutment with the armature when the latter is disposed in the corresponding seat, energizing coils encircling said second and third pole pieces and operable when activated to produce an energizing flux attracting the armature against the seat between the pieces, and a signal coil encircling said first piece to produce flux cooperating with said energizing flux to provide different resultant fluxes attracting said armature into the respective seats adjacent the first piece when the coil is energized in opposite senses.

3. A relay having, in combination, a core of magnetic material having angularly spaced first, second and third pole pieces connected together magnetically and converging toward but terminating short of each other to define a cavity with an air gap between each pair of adjacent pole pieces, a freely movable armature of magnetic material disposed within and smaller than said cavity and adapted to conduct electric current, a plurality of abutments rigid with said pole pieces and facing inwardly toward said cavity to engage said armature and define three angularly spaced seats therefor each disposed between two adjacent pole pieces, flux means operable to produce an energizing flux in the gap between said first and second pole pieces to attract said armature into the corresponding seat between the pieces, signal coil means encircling part of said core and operable to produce flux cooperating with said energizing flux to attract said armature into the seat between said third and first pole pieces when the coil means is energized in one sense and into the seat between said third and second pole pieces when the coil means is energized in the opposite sense, and contact means engageable with said armature to complete an electric circuit therethrough when the armature is in each of said seats adjacent said third pole piece.

4. A relay having, in combination, a core of magnetic material having three angularly spaced pole pieces converging toward and terminating short of each other in end faces defining a cavity, said pole pieces being connected magnetically at points spaced from said faces, an armature smaller than and freely movable within said cavity, abutments rigid with said pole pieces and defining three angularly spaced seats for said armature each disposed between two different pole pieces, energizing coils

- encircling parts of said core and operable when energized to produce an energizing flux in two of said pole pieces attracting said armature into the seat between the pieces, a signal coil encircling another part of said core and operable to provide a flux in the third pole piece cooperating with said energizing flux to produce resultant fluxes attracting the armature into the respective seats adjacent the third piece when the coil is energized in opposite senses, and contact means cooperating with said armature to complete a different electric circuit when the armature is in each of said seats adjacent said third pole piece.
5. A relay having, in combination, a magnetic core having first, second and third pole pieces terminating in pole faces angularly spaced around and defining a cavity with an air gap between each pair of adjacent pieces, magnetic connections between said pole pieces at points spaced from said faces, a freely movable armature of magnetic material disposed within and smaller than said cavity, abutments rigid with said pole pieces and facing toward said cavity to engage said armature and define three angularly spaced seats for the armature each disposed between two different ones of said pole pieces, flux means providing an energizing flux in said first and second pole pieces to attract said armature into the gap and the corresponding seat between the pieces, signal flux means operable to provide a flux in said third pole piece cooperating with said energizing flux to produce a resultant flux attracting said armature against the seat between the third and first pole pieces when the means is energized in one sense and a resultant flux attracting the armature against the seat between the third and second pole pieces when the means is energized in the opposite sense, and contact means cooperating with said armature to complete an electric circuit when the armature is in each of said seats adjacent said third pole piece.
